TOILET DEODORIZER

James R. Herriott, Alamo, Calif.

Application September 4, 1956, Serial No. 42,812

Term of patent 14 years

(Cl. D16—2)

Fig.1.

Fig.2.

Fig.4.

I claim:

The ornamental design for a toilet deodorizer, substantially as shown.
